UNITED STATES PATENT OFFICE.

EDMOND A. VON KAENEL, OF CHICAGO, ILLINOIS.

ASH-RECEIVER.

1,172,411.

Specification of Letters Patent. Patented Feb. 22, 1916.

Application filed February 17, 1913. Serial No. 748,801.

To all whom it may concern:

Be it known that I, EDMOND A. VON KAENEL, a citizen of the United States, residing at Chicago, in the county of Cook and State of Illinois, have invented certain new and useful Improvements in Ash-
10 Receivers, of which the following is a specification.

This invention relates to an ash receiver
10 which includes the functions of a box or container, and may be made of any suitable material such as tin, paper or card-board.

The object of my invention is to provide a receptacle one of the walls of which will serve as a cigar, cigarette or match support, and the tray of which will form a container for ashes, cigars or cigarettes.

I attain the above object by the device illustrated in preferred form in the accompanying drawing, in which:—

Figure 1 is a perspective view of my ash receiver with the tray partially withdrawn and open; Fig. 2 is a top plan view showing the supporting tongues before being bent into operative position, and Fig. 3 is a longitudinal central section of my ash receiver.

Similar reference characters refer to similar parts throughout the several views.

The reference character 4 designates the body of the receiver or container which may be made of thin sheet metal, or preferably of paper, rectangular in cross section and open at one end to receive the tray 5. The top wall of one side of said body is cut or scored along the lines 4^b, forming the inverted V-shaped tongues 4^a, which, when bent upwardly along the lines 4^c, as shown in Fig. 1, form supports for cigarettes, cigars, or matches, as may be desired. The upper wall 5^a of the tray or drawer 5, serves to form the bottom of the ash receiver, but when entirely withdrawn, the bottom or opposite side of the body portion 4 of the box,

will serve the same purpose. When it is 45 not desired to use the device to receive ashes and support cigarettes, &c., the flaps 4^a will be folded back to their flat or normal position, so that the device may be restored to the user's pocket. The ashes which fall 50 through the opening left by the upturned flaps may remain in the receiver until it is convenient to remove them. The angles between the flaps 4^a will be so proportioned that a cigarette placed therein will be supported at a sufficient distance from the container or tray to prevent scorching or burning of the latter where the article is made of paper or card-board.

It will be obvious that instead of making 60 the receivers with the cuts 4^b therein, the lines for such cuts may be indicated in some appropriate manner, and the user may make the cuts when convenient.

Having thus described my invention, what 65 I claim as new, is:—

1. A combined cigarette box and ash tray comprising a box, one wall whereof is provided with a plurality of radiating incisions so that the portions of the wall on the sides 70 of each incision may be bent outwardly to provide angular recesses between the edges of the outwardly bent portions.

2. A combined cigarette box and ash tray comprising a box, a tray slidably mounted 75 therein, the upper wall of said box being provided with a plurality of intersecting incisions so that the portions of the wall on the sides of each incision may be bent outwardly to provide substantially V-shaped 80 recesses between the edges of the outwardly bent portions.

In testimony whereof I affix my signature in the presence of two witnesses.

EDMOND A. VON KAENEL.

Witnesses:

F. BENJAMIN,

M. A. MILORD.
